UNITED STATES PATENT OFFICE.

EUGENE F. HELM, OF MONTPELIER, INDIANA.

DEVICE FOR CONNECTING RODS.

No. 833,386.

Specification of Letters Patent.

Patented Oct. 16, 1906.

Application filed January 12, 1906. Serial No. 295,819.

To all whom it may concern:

Be it known that I, EUGENE F. HELM, a citizen of the United States, residing at Montpelier, in the county of Blackford and State of Indiana, have invented certain new and useful Improvements in Devices for Connecting Rods, of which the following is a specification.

The great majority of the devices in common use for connecting rods require that the ends of the rods be provided with a head, and this feature has been found to add very materially to the cost of applying the devices.

The object of the present invention has accordingly been to provide an improved rod-connecting device by means of which rods can be quickly and rigidly connected just as they are turned from the rolling-mill and without the extra expense of providing their ends with heads.

While this device has been especially designed for connecting the ends of the pull-rods employed for transmitting power from a central source to a plurality of oil-wells, it must be understood that I do not limit myself to this use, since it may be employed with equal facility for connecting rods, tubes, steel cables, or similar articles wherever such a device is needed.

For a full description of the invention and the merits thereof and also to acquire a knowledge of the details of construction of the means for effecting the result reference is to be had to the following description and accompanying drawings, in which—

Figure 1 is a longitudinal sectional view through the connecting-clamp. Fig. 2 is a transverse sectional view through the same, and Fig. 3 is a detail perspective view showing the clamping members when taken apart.

Corresponding and like parts are referred to in the following description and indicated in all the views of the drawings by the same reference characters.

The numerals 1 and 2 designate the two similar clamping members which form the body of the rod-connecting device. Each of the clamping members 1 and 2 is provided on its inner face with a longitudinal groove or depression 3, which is shown as being approximately semicircular in cross-section and which is adapted to receive a portion of the rods to be connected. A transverse projection or ear 4 projects from the inner face of each of the clamping members 1 and 2 at one end thereof. These projections 4 are per-

rated to receive the ends 5 of the rods, which are connected and preferably take the form of arches, as shown in the drawings. The innerfaces of the arches form a continuation of the sides of the grooves 3, while the outer sides of the arches are spaced from the edges of the clamping members, as seen at 6. It will also be observed that threaded stems 7 project from the crowns of the arches or the heads of the projections 4. The opposite ends of the clamping members 1 and 2 to those provided with the projections 4 are formed with transverse openings 8 and are cut away to form a recess or cavity 9. The clamping members 7 are preferably enlarged around the openings 8, as seen at 10.

In the application of the device the ends 5 of the pull-rods are passed through the openings in the projections 4 upon the opposite clamping members 1 and 2, and the stems 7 upon each of the clamping members are passed through the openings 8 in the opposite clamping member. Nuts 11 are then screwed upon the threaded stems 7 and the clamping members 1 and 2 forced tightly together, so as to take a secure grip upon the rods and form a rigid connection between them. It will thus be seen that the cavity 9 at one end of each of the clamping members 85 forms a housing for the projection or arch 4 upon the opposite clamping member and enables the two clamping members to be brought closely together for a secure engagement with the rods.

Having thus described the invention, what is claimed as new is—

1. In a device of the character described, the combination of two members to be connected, a pair of clamping members fitting upon opposite sides of the adjacent ends of the members to be connected, a projection from one of the clamping members provided with an opening to receive the end of one of the members to be connected, the opposite clamping member being provided with a cavity to receive said projection, means for securing a connection between the clamping members and the opposite member to be connected, and means for forcing the clamping members into a close engagement with the members to be connected.

2. In a device of the character described, the combination of two members to be connected, clamping members fitting upon opposite sides of the adjacent ends of the members to be connected, a projection upon one

- of the clamping members provided with an opening to receive the end of one of the members to be connected, a threaded stem upon the head of said projection, the opposite 5 clamping member being provided with an opening through which the threaded stem passes, means for securing a connection between the clamping members and the opposite member to be connected, and a nut co-
operating with the threaded stem to force 10 the clamping members into a close engagement with the members to be connected.
3. In a device of the character described, the combination of two members to be connected, 15 a pair of clamping members fitting upon opposite sides of the adjacent ends of the members to be connected, said clamping members being provided on their inner faces with longitudinal grooves into which the 20 members being connected fit, an arch spanning the groove in one of the clamping members and forming an opening to receive the end of one of the members to be connected, the opposite clamping member being provided with a cavity to receive the arch, 25 means for securing a connection between the clamping members and the opposite member to be connected, and means for forcing the clamping members into a close engagement 30 with the members being connected.
4. In a device of the character described, the combination of two members to be connected, 35 a pair of clamping members fitting upon opposite sides of the adjacent ends of the members to be connected, said clamping members being provided on their inner faces with grooves in which the members to be connected fit, an arch spanning the groove at 40 one end of each of the clamping members and forming openings through which the members to be connected are passed, threaded stems projecting from the crowns of the arches, the opposite end of each of the clamping members being provided with an opening 45 to receive the threaded stem projecting from the opposite clamping member, and nuts co-operating with the threaded stems to force the clamping members into a close engagement 50 with the members to be connected.
5. In a device of the character described, 55 the combination of two members to be connected, a pair of clamping members fitting upon opposite sides of the adjacent ends of the members to be connected, a projection at 60 one end of each of the clamping members,

said projections being provided with openings through which the members to be connected are passed, the opposite end of each of the clamping members being provided with a cavity to receive the projection upon the opposite clamping member, and means for 65 forcing the clamping members into a close engagement with the members to be connected.

6. In a device of the character described, 70 the combination of two members to be connected, clamping members fitting upon opposite sides of the adjacent ends of the members to be connected, a projection upon one end of each of the clamping members, said projections being provided with openings 75 through which the members to be connected are passed, a threaded stem projecting from the head of each projection, the opposite end of each of the clamping members being provided with an opening through which the 80 threaded stem upon the opposite clamping member is passed and also with a cavity to receive the projection upon the opposite clamping member, and nuts co-operating with the threaded stems to force the clamping members into a close engagement with the members to be connected.

7. In a device of the character described, 85 the combination of two members to be connected, a pair of clamping members fitting upon opposite sides of the adjacent ends of the members to be connected, said clamping members being provided on their inner faces with grooves in which the members to be connected fit, an arch spanning the groove at 90 one end of each of the clamping members and forming openings through which the members to be connected are passed, threaded stems projecting from the crowns of the arches, the opposite end of each of the clamping members being provided with an opening 95 to receive the threaded stem projecting from the opposite clamping member, and nuts co-operating with the threaded stems to force the clamping members into a close engagement 100 with the members to be connected.

In testimony whereof I affix my signature in presence of two witnesses.

EUGENE F. HELM. [L. S.]
